Rudolf Kildermann

ATTORNEY.

UNITED STATES PATENT OFFICE

WILHELM LAMP, OF NEW YORK, N. Y.

SCREEN CURTAIN

Application filed February 20, 1928. Serial No. 255,546.

My invention relates to window screens which serve to protect buildings against the entry of mosquitoes and similar vermin and the objects of my invention are, first, to have 5 the screen, conveniently, on the inside of the window, second, to be able to remove it by an operation as simple as that of lowering and raising a window shade, third, to have the window completely protected by the 10 screen, when it is closed, so that no objectionable insects can enter at any point of the window, fourth, to allow the use of a screen which can be washed and kept clean like any other cloth fabric, fifth, to provide a 15 screen which can be made attractive and which, in color and design, can be kept in harmony with the interior decorations, sixth, to have a screen that does not require mounting and dismounting between seasons, and 20 seventh, to have the screen completely removed from sight and protected from dirt when it is not in use.

To attain these objects I use the mechanism and arrangement illustrated in the accompanying drawing in which:

Figure 1 shows the indoor front elevation of a window frame into which my invention is installed; the curtain screen is closed.

Figure 2 shows the corresponding sectional 30 side view.

Figure 3 shows an enlarged and detailed view of the left half of the upper part of the elevation shown in Figure 1; but in this view the screen curtain is fully open. The 35 right symmetrical half of the elevation is omitted.

Figure 4 shows the side view corresponding to Figure 3.

Figure 5 is the bottom view of a corner of the half shown in Figures 3 and 4.

Figure 6 is part of the front view of the back plate of the part which serves to reinforce and guide the curtain at the bottom.

Figure 7 is part of the top view of a wire 45 insert for the lower seam of the screen curtain.

Figure 8 shows a corner of the screen curtain.

Similar numerals refer to similar parts 50 thruout the several views.

Against the top 9 of the window frame is fastened the box 10; that box is open in the back; the ends, 11, which are set into the box for a short distance, have slots, 12, suitably inclined to support the ends of the curtain 55 roller 13. One of these ends is a round pin, the other end 14 is flattened out, and a suitable tension on the inside of the curtain roller, reacting upon the flat end 14 serves to keep the curtain rolled up normally, a mechanism which is well known to those acquainted with the art of roller curtain construction. The ratchet movement, for a stagger stop, which is also common to roller curtains and which serves to set them at any desired point, 60 is omitted in my construction. The curtain, consisting of cloth netting, 15, is suitably fastened to the curtain roller at one end and its meshed cloth has a hollow seam 16 on the sides and it has a similar seam 17 at the 70 bottom which opens at the ends into said seam 16. Wire hook 18 with eyes 19 at the ends is inserted in seam 17 and the eyes 19, when horizontal, fill the tubular inside of seam 16. Eyes 19 as well as the tubular 75 ends 20 of metal sheet 21 fit slidably over the vertical rods 22; these rods are rounded off at their upper ends 29 just below metal box 10 and stand in a vertical shielding enclosure 23 formed by a tensile back shield 24 and a similar front shield 25, both of which are assembled over and fastened to the strip 26. The edges 27 and 28 of those shields are beaded. Enclosure 23 is fastened to side 30 80 of the frame. The other enclosure on the 85 opposite side of the frame is similar in construction but of course reversed. Beaded edges 27 and 28 are slightly bent back, away from each other, at their upper ends. The front shield 25 ends below the box 10. But 90 the shield 24 extends a short distance above the beaded edge 31 of said box. The shields 24 and 25, which form the enclosures 23, are so arranged that they incase the rods 22 and the end portions of the wire hook 18, and the plate member 21, respectively, and at 95 their beaded edges 27 and 28, snugly fit against the front and back of the screen curtain, near the opposite edges thereof, with a spring pressure which permits the free 100

vertical movement of the curtain, but, at the same time, makes such a closing of the joint between the curtain and the shields, that mosquitoes or other insects may not gain passage therethrough.

5 The upper and lower edges 32 and 33 of metal sheet 21 are beaded over to a width slightly short of the distance between the shielding enclosures 23 formed by the shields 10 24 and 25. The length of cover 34 equals the length of those beaded edges and the width of that cover is such that its bent lower edge 35 and the bead 36 at its upper edge, when fitted over part 21, leave room for passage 15 of curtain 15 between the beads 32 and 36. These parts are held together by knobs 37 tightened down over the screws 38 which form one piece with metal sheet 21, and pass through clearance holes in cover 34. There 20 is a hole or recess 39 in the center of cover 34 into which snaps the hook on latch 40 when the curtain is pulled all the way down and rests on window sill 41. 42 and 43 are the top rail and stiles of the sash framing glass 25 44.

Box 10, shielding enclosures 23 with rods 22 and with plate 21 slidably connected to said rods 22, and latch 40 are permanently mounted in the frame.

30 To put up the screen curtain, its end is fastened to and it is rolled up onto the curtain roller 12 and the other end of the curtain is prepared by the insertion of the wire 18 into the seam 17. Then the curtain roller is 35 mounted in the box as shown and the end with the wire is pulled down over the beaded edge 31 of the box. I then raise plate 21 to a point just below the box and lay the lower seam of the curtain with the wire in it upon 40 the plate so that the wire rests below bead 32 and the eyes 19 on the end of the wire rest upon the tubular ends 20. Then cover 34 is clamped upon the plate 21 by knobs 37. If I pull down now, gripping the lower end of 45 the curtain at the knobs 37, eyes 19 and the seams 16 of the curtain slide down over the rounded ends 29 of rods 22 and plate and curtain slide down between the beads 27 and 28. When the curtain is pulled down as far 50 as possible latch 40 trips into 39 and the screen is in position. To remove the cloth screen for the purpose of washing or to replace it by a new curtain, the procedure is reversed.

55 Whereas for a clear description of my invention I have above set forth the exact details of the construction, I do not want to limit the scope of my invention to the very design described but I claim:

60 In a window screen, a fabric curtain, tubular seams bordering the sides of said curtain, a transverse tubular seam at the lower end of said curtain, the ends of it opening into said longitudinal seams, a wire removably 65 extending through the length of said trans-

verse seams, eyelets on the ends of said wire cross sectionally reenforcing said longitudinal seams, a reenforcing sheet metal cross-bar, cross sectionally substantially conformed to said wire and eyelets, said cross-bar closing 70 over said wire and at the ends registering with said eyelets, vertical rods near the sides of said window slidably fitting said longitudinal seams, eyelets, and said ends of said cross bar, and shields extending from the 75 sides of said window over said rods, slidably closing over said curtain, wire and cross bar when they are forked to surround said rod.

Signed at New York, in the county and State of New York, this 18th day of February, A. D. 1928.
